UNITED STATES PATENT OFFICE.

FRANK A. LANDEE, OF MOLINE, ILLINOIS.

WIRE-STRETCHER.

SPECIFICATION forming part of Letters Patent No. 399,053, dated March 5, 1889.

Application filed September 19, 1888. Serial No. 285,832. (No model.)

To all whom it may concern:

Be it known that I, FRANK A. LANDEE, a citizen of the United States, and residing at Moline, in the county of Rock Island and State of Illinois, have invented a certain new and useful Improvement in Wire-Stretchers, which is fully set forth in the following specification, reference being had to the accompanying drawings, in which—

10 Figure 1 is a side elevation of the eccentric-clamp of my wire-stretcher; Fig. 2, a transverse sectional view taken on the line $x-x$ of Fig. 1, and Fig. 3 an end view of the same.

Like letters refer to like parts in all the figures of the drawings.

15 The object of my invention is to make a cheap, simple, and durable mechanism for clasping a telegraph-wire or fence-wire securely and readily for the purpose of holding it or stretching it while it is being secured or mended. Any suitable well-known device may be attached to my eccentric-clasp for the purpose of applying power to stretch the wire.

20 In the accompanying drawings, A represents the frame or body of my eccentric-clasp for clasping the wire made preferably from metal. The enlarged end is provided with a projecting shoulder, B, and the opposite end is provided with a loop or guide, C.

25 D is a pin firmly secured to the frame or body A, projecting at a suitable distance from the shoulder B to receive the eccentric E, which is pivoted thereon.

30 F is a metal bar pivoted at one end to the eccentric E by means of the pin G, as clearly shown in Figs. 1 and 3. This bar F passes through the loop C loosely, so that while it is held in position by said loop and the pivoted pin G it readily slides back and forth to operate the eccentric-cam E to grasp and release the wire between the eccentric-cam E and the shoulder B. It will be observed that while that portion of the bar F which passes through the loop C is straight 35 and in line with the body of the stretcher the end of said bar, which is pivoted to the cam E, is curved or deflected laterally. This construction permits the straight portion of the bar to slide freely through the inclosing-loop 40 without binding, while at the same time it

permits the other end to be attached to the cam E at such a distance from its pivot as will give a satisfactory leverage to obtain a strong grip.

45 H represents an eye at the end of the bar F for readily attaching said bar to the chain or rope of a pulley-block or windlass or other suitable device for applying power to clasp and stretch the wire or other article which it may be desired to clasp and stretch.

50 By applying power to the slide-bar F the eccentric-cam E is caused to turn on its pivot D and clasp between it and the shoulder B the wire which it is desired to stretch, and the greater the power or the strain upon the 55 bar F the more firmly the wire is clasped between the eccentric-cam E and shoulder B. When the wire is fastened, then the strain on the bar F is released, and by its reverse motion the eccentric-cam E releases the clasp 60 on the wire.

55 As hereinbefore stated, the bar F is held in position by the loop or guide C, so that it is permitted to have the slight lateral motion due to the movement of its pivoted end in the 75 arc of a circle. The loop or guide holds it, however, with sufficient firmness to prevent it or the cam from dropping, and I am thus enabled to operate the whole device with one hand while applying it to or removing it from 80 the wire, thus leaving the other hand free to operate the wire.

65 I have an implement that is composed of three parts, all of which are strong, durable, and efficient, cheaply made, and so simple in 85 its operation that it is conveniently and readily operated.

70 It is obvious that various modifications in the details of construction may be made without departing from the principle of my invention, and I therefore do not wish to be understood as limiting myself strictly to the precise details hereinbefore described, and shown in the drawings.

75 Having thus described my invention, what 95 I claim as new, and desire to secure by Letters Patent, is—

80 A wire-stretcher composed of the straight frame or body A, arranged longitudinally in the line of draft and provided at one end with 100

the guiding-loop C and at the other end with the lateral projection D, the cam E, pivoted on said frame or body opposite said projection, and the bar F, having one end curved or 5 deflected laterally and pivoted to the cam, and its remaining portion arranged in the line of draft and passing through and embraced

by the loop which serves to support and guide said bar, substantially as and for the purposes specified.

FRANK A. LANDEE.
